FIG. 1 is a front perspective view of an overhead storage unit in a closed position according to our design;

FIG. 2 is a top plan view thereof;

FIG. 3 is a front elevational view thereof;

FIG. 4 is a bottom view thereof;

FIG. 5 is a rear elevational view thereof;

FIG. 6 is an end elevational view of the right side of the cabinet, the left side elevational view being identical thereto except for being a mirror image thereof; and,

FIG. 7 is a front perspective view thereof, corresponding to FIG. 1, but showing the door of the cabinet in an opened position.
